UNITED STATES PATENT OFFICE.

BARNETT SHATZ, OF BUENOS AIRES, ARGENTINA.

RULER BLOTTER.

1,413,794.

Specification of Letters Patent. Patented Apr. 25, 1922.

Application filed December 28, 1920. Serial No. 433,687.

To all whom it may concern:

Be it known that I, BARNETT SHATZ, citizen of the United States, residing at 25 de Mayo Street No. 214, Buenos Aires, Argentina, have invented new and useful Improvements in a New Type of a Ruler Blotter, of which the following is a specification.

This invention relates to improvements in rulers and more particularly to rulers having means for absorbing the ink which may flow over the ruling edge of the same.

The primary object of the present invention is to furnish an ordinary ruler with means for use in absorbing any ink which may flow over the ruling edge, and which may also be used for blotting the lines drawn by the aid of said ruler.

With the foregoing object outlined and with other objects in view which will appear as the description proceeds, the invention consists in the novel features hereinafter described in detail, illustrated in the accompanying drawing, and more particularly pointed out in the appended claims.

25 Referring to the drawing:

Figure 1 is a top plan view of one end portion of a ruler having my improvements applied thereto.

Fig. 2 is a transverse sectional view taken 30 on line 2—2 of Figure 1.

Fig. 3 is a longitudinal sectional view taken on line 3—3 of Fig. 1.

In the drawing, 8 designates an ordinary ruler having a beveled edge 9 terminating 35 in a ruling edge 15. In using a ruler of this ordinary construction for the purpose of drawing lines and the like, it frequently happens that the ink overflows the edge 15 and forms a blot on the paper being ruled.

40 In order to overcome this disadvantage, I have provided the following improvement.

On the underside of the ruler I place a sheet or strip 13 of blotting paper, and the front edge 14 of this paper is arranged in 45 close proximity to the edge 15 of the ruler, so that any ink flowing over the edge 15 will be absorbed by the blotting paper.

In order to secure this blotting paper to the ordinary ruler, I preferably place ad-

hesive on one side of the blotting paper to 50 cause the same to adhere to a strip of cloth 10 which is placed on the underside of the ruler 8 and has its end portions 10^a folded around the ends of the ruler. The ends 10^a of the cloth are secured in position by clips 55 or plates 12 which clamp the ends 10^a within recesses 11 provided in the upper face of the ruler. It will be noted that each recess is in the form of a dove-tail so that the plate 12 may be secured in position by sliding the 60 same longitudinally of the groove.

From the foregoing I believe that the construction, operation and advantages of the invention may be readily understood, and I am aware that various changes may be 65 made in the construction illustrated without departing from the spirit of the invention as expressed in the following claims.

1. A ruler having on its upper side and near one end of the same, a transverse 70 groove, a blotting device arranged on the underside of the ruler and having an end member extending around one end of the ruler and arranged in said groove, and a member arranged in the groove and engaging 75 said end member for securing the blotting device in position.

2. The combination with an ordinary ruler having a dove-tail groove in its upper surface arranged near one end of the ruler, 80 and extending transversely across said ruler, a cloth strip arranged on the underside of the ruler and having an end portion extending around one end of the ruler and engaging said groove, a member arranged in 85 said groove and engaging the end portion of the cloth for holding the same in said groove, and a strip of blotting paper secured to said cloth strip and having an edge arranged in 90 close proximity to the ruling edge of said ruler.

In testimony whereof I have signed my name to this specification in the presence of two subscribing witnesses.

BARNETT SHATZ.
